UNITED STATES PATENT OFFICE

2,046,003

ENGINE

Philip Lane Scott, Chicago, Ill.

Application August 3, 1931, Serial No. 554,720

7 Claims. (Cl. 123—32)

My invention relates to an improved method and apparatus for atomizing, mixing and burning liquid fuel. It is adapted to engines of the internal combustion type, particularly those operating on the Diesel cycle, or in general by the injection of fuel with or without compression ignition.

One object of my invention is to provide a method of positively atomizing fuel and simultaneously mixing the atomized fuel with air. Another object of the invention is to provide for sufficient atomization and mixture in a positive manner, particularly with respect to the mixing process. Another object of my invention is to provide a simple arrangement of atomizing and mixing apparatus of such form as to promote very high output for a given volume of combustion space together with good fuel consumption.

Other objects will appear from time to time during the course of the specifications and claims.

For the purpose of illustration, a two-cycle single acting Diesel engine is shown with the apparatus, which is the subject of my invention, applied thereto. While this is an entirely operable and suitable construction it will be understood that the system may be applied to a wide variety of engines and even to other combustion apparatus without departing from the spirit of the invention.

The drawing shows an elevation in section of an engine together with the atomizing and mixing apparatus.

A is a crank case in which is journaled a crank shaft A¹ which is driven by a connecting rod A³, acting on a crank pin A². A⁴ is a piston carried on the end of the connecting rod opposite the crank. This apparatus forms conventional reciprocating engine structure.

B is a cylinder having an exhaust port B¹ and an air scavenging and supply port B². Air is supplied to the port B² by any method commonly used in engines of this type, and is not shown since it forms no essential part of the invention. B³ is a cylinder head having a water jacket B⁴. B⁵ is a main combustion space formed within the cylinder head B³. B⁶ is an air duct or nozzle designed to convey air with a minimum friction loss toward the main chamber B⁵. B⁷ is a restriction between the air passage B⁶ and the chamber B⁵, which may or may not form a part of the structure.

C is a cylinder containing within it a piston C¹ and joined to the duct B⁶ by a passage C². The piston C¹ is driven by a short rod C³, a bell crank C⁴ and a push rod C⁵. The push rod C⁵

is guided in an extension B⁸ of the cylinder head B¹. The push rod C⁵ is in turn driven by a cam C⁶ mounted on a lay shaft C⁷, which shaft is driven from the engine crank shaft by the gear train C⁸, C⁹, C¹⁰. 5

D is a fuel atomizing valve positioned with its nozzle or tip D¹ at the entrance to the combustion chamber B⁵. This valve is supplied with liquid fuel under suitable pressure through a pipe D² and fuel pump D³ which may be of any form 10 commonly used with such engines. This pump is driven by the gear D⁴ from the gear C⁸. It receives fuel through the fuel inlet pipe D⁵ in any conventional manner.

The use and operation of my invention is as follows: The engine shown in the drawing is assumed to have conventional air and fuel supply and other customary adjuncts and to be started by any customary means. Upon an up-stroke of the piston, A⁴, air is compressed in the usual 20 manner into the combustion space B⁵. The compression may be to a point sufficient to ignite fuel atomized through any common form of nozzle D. It is not necessary, however, to carry out the process that compression be raised to the ignition 25 temperature, as the apparatus may be used in conjunction with engines employing electric ignition or hot surfaces. This air under pressure, filling the passages B⁶ and C², exerts pressure upon the piston C¹, tending to force it outwardly 30 and fill the cylinder C with a portion of the air charge. This outward motion of the piston is permitted through the motion of the driving linkage controlled by the cam C⁶. This cam C⁶ is so positioned with relation to the crank shaft 35 A¹, through its train of gears that its return face will permit the auxiliary piston C¹ to recede at some desired time during the compression stroke.

At or near the end of the compression the main piston A⁴ will be in an upward position, the auxiliary piston will be in an outward position and the compressed air charge will lie partly within the main combustion space B⁵ and partly within the cylinder C together with a small quantity in the connecting ducts. The amount of the air 45 charge held in the auxiliary cylinder C will be proportioned, with relation to the main charge, according to the particular requirements of the engine. It is a matter to be determined individually for each separate engine design. With 50 the air charge so divided and the main piston in proper position for the injection of fuel, delivery of fuel is begun by means of the fuel pump D³ to the valve D, atomization taking place at the nozzle tip D¹. At or about the time the discharge 55

of atomized fuel commences, from the tip D¹ into the combustion space B⁵, the auxiliary piston C¹ begins a return stroke, forcing substantially all the air in the cylinder C through the ducts C² and B⁶, and into the main chamber B⁵. This delivery of air during atomization of the fuel is for the purpose partly of providing necessary air for combustion, and partly to create a controlled air flow of an intensity and direction such as to promote thorough mixing between the fuel and the entire volume of air enclosed within the combustion space. To aid in obtaining the desired direction and velocity, a throat B⁷ may be provided in which the tip of the fuel valve may be approximately centered. The question of the quantity of air, its velocity and direction are matters which must be determined for each engine designed. The principle involved is that there shall be a substantial controlled delivery of air at or about the time of injection and substantially in a manner to assist to best advantage the dispersion of atomized fuel. It will be seen that the auxiliary piston may develop, upon its portion of the air charge, any desired pressure, but in practice the determining factor will be that there will be only sufficient pressure to promote adequate mixing of the atomized fuel with the full air charge. It will further be noted that this air supply system is in no wise directly used to atomize the liquid fuel though it may have an indirect additive effect in the process of fuel atomization. The fuel is primarily atomized and delivered to the combustion space by a separate system.

It will be seen that the shape of the combustion chamber, the position of the fuel valve, and the position of the auxiliary chamber together with the associated driving mechanism may take a very wide variety of forms depending upon the particular requirements of individual designs without departing from the spirit of the invention.

I claim:

1. In an engine, a main cylinder, a piston mounted to reciprocate therein, means to operate said piston to compress air therein, a separate and distinct combustion chamber having communication with the main cylinder, a fuel nozzle positioned to discharge fuel into the combustion chamber, an auxiliary cylinder, means interposed between the auxiliary cylinder and said combustion chamber defining an air nozzle discharging into the combustion chamber, and means operable to transfer air from the main cylinder to the auxiliary cylinder, said last mentioned means including an auxiliary piston mounted to reciprocate within the auxiliary cylinder, and means for reciprocating said auxiliary piston to intermittently deliver the air from the auxiliary cylinder into the combustion chamber through said air nozzle.

2. In an engine, a main cylinder, a piston mounted to reciprocate therein, means to operate said piston to compress air therein, a separate and distinct combustion chamber having communication with the main cylinder, a fuel nozzle positioned to discharge fuel into the combustion chamber, an auxiliary cylinder, means interposed between the auxiliary cylinder and said combustion chamber defining an air nozzle surrounding the fuel nozzle and discharging into the combustion chamber, and means operable to transfer air from the main cylinder to the auxiliary cylinder, said last mentioned means including an auxiliary piston mounted to reciprocate

within the auxiliary cylinder, and means for reciprocating said auxiliary piston to intermittently deliver the air from the auxiliary cylinder into the combustion chamber through said air nozzle.

3. In an engine, a main cylinder, a piston mounted to reciprocate therein, means to operate said piston to compress air therein, a separate and distinct combustion chamber having communication with the main cylinder, a fuel nozzle positioned to discharge fuel into the combustion chamber, an auxiliary cylinder, means interposed between the auxiliary cylinder and said combustion chamber defining an air nozzle discharging into the combustion chamber, said combustion chamber at the point of communication with said air nozzle being formed with a constriction defining a throat surrounding the fuel nozzle, and means operable to transfer air from the main cylinder to the auxiliary cylinder, said last mentioned means including an auxiliary piston mounted to reciprocate within the auxiliary cylinder, and means for reciprocating said auxiliary piston to intermittently deliver the air from the auxiliary cylinder into the combustion chamber through said air nozzle.

4. In an engine, a main cylinder, a main piston mounted to reciprocate therein, means for operating said main piston to compress air within the main cylinder, a combustion chamber positioned beyond the confines of the main cylinder having direct and free communication with the main cylinder, the combustion chamber being of small cross-sectional area in comparison to that of the main cylinder, an auxiliary cylinder having its axis disposed transversely of the axis of the combustion chamber, a passage of relatively large cross-sectional area providing communication between the auxiliary cylinder and the combustion chamber whereby to permit the non-turbulent transfer of large quantities of air between the combustion chamber and the auxiliary cylinder, a piston within the auxiliary cylinder and means to reciprocate the same to intermittently deliver the air from the auxiliary cylinder.

5. In an engine, a main cylinder, a main piston mounted to reciprocate therein, means for operating said piston to compress air within the main cylinder, a separate combustion chamber comprising substantially all of the clearance volume of the main cylinder disposed outside the confines of the main cylinder and having free and open communication with the main cylinder, said combustion chamber being of substantially smaller cross-sectional area than that of the main cylinder, a fuel atomizing system terminating in an atomizing nozzle, an auxiliary cylinder of substantial volume with respect to the volume of the combustion chamber having its axis disposed transversely of the axis of the combustion chamber and connected to the combustion chamber by a short non-turbulent air passage, said atomizing nozzle extending through said non-turbulent air passage and being positioned to discharge fuel into the combustion chamber, a piston mounted in the auxiliary cylinder and adapted to transfer air back and forth through said air passage, and means for reciprocating the piston in the auxiliary cylinder to remove air from and to deliver the air to the combustion chamber.

6. In an engine, a main cylinder, a main piston mounted to reciprocate therein, means for operating said piston to compress air within the main cylinder, a separate combustion chamber comprising substantially all of the clearance volume of the main cylinder disposed outside the con-

7. In an engine, a main cylinder, a main piston mounted to reciprocate therein, means for operating said piston to compress air within the main cylinder, a separate and distinct substantially conical combustion chamber comprising substantially all of the clearance space of the main cylinder, said combustion chamber having free and open communication with said main cylinder at 5 substantially the point of maximum cross-sectional area of said combustion chamber, a fuel atomizing system including an atomizing nozzle positioned to discharge fuel into the combustion chamber, an auxiliary cylinder of sub- 10 stantial volume with respect to the volume of the combustion chamber having its axis disposed transversely of the axis of the combustion chamber and connected to the combustion chamber by a short non-turbulent air passage comprising an extension of the combustion chamber and disposed substantially coaxially thereof, said atomizing nozzle extending through said non-turbulent air passage and being positioned substantially 15 centrally of said passage and substantially axially of said combustion chamber to discharge fuel into the combustion chamber, a piston mounted in the auxiliary cylinder and adapted to transfer air back and forth through said air passage, and means for reciprocating the piston in the auxiliary cylinder to remove air from and to deliver the air to the combustion chamber.
7. In an engine, a main cylinder, a main piston mounted to reciprocate therein, means for operating said piston to compress air within the main cylinder, a separate and distinct substantially conical combustion chamber comprising substantially all of the clearance space of the main cylinder, said combustion chamber having free and open communication with said main cylinder at 5 substantially the point of maximum cross-sectional area of said combustion chamber, a fuel atomizing system including an atomizing nozzle positioned to discharge fuel into the combustion chamber, an auxiliary cylinder of sub- 10 stantial volume with respect to the volume of the combustion chamber having its axis disposed transversely of the axis of the combustion chamber and connected to the combustion chamber by a short non-turbulent air passage comprising an extension of the combustion chamber and disposed substantially coaxially thereof, said atomizing nozzle extending through said non-turbulent air passage and being positioned substantially 15 centrally of said passage and substantially axially of said combustion chamber to discharge fuel into the combustion chamber, a piston mounted in the auxiliary cylinder and adapted to transfer air back and forth through said air passage, and means for reciprocating the auxiliary piston to remove air from and to deliver the air to the combustion chamber.

PHILIP LANE SCOTT. 25
